UNITED STATES PATENT OFFICE

2,378,400

PIPE

Fred W. Gans, Trenton, N. J.

Application July 25, 1940, Serial No. 347,388

11 Claims. (Cl. 131—183)

This invention relates to improvements in tobacco pipes and particularly to an ejector device which is operated in a novel manner and at the same time enables the smoker to have greater smoking enjoyment and unusual benefits through the medium of the ejector operating means.

Heretofore tobacco pipes have been constructed with ejector devices positioned in the bowl, and these ejector devices are operated by means of a pivoted, moveable member normally disposed along the bottom of the pipe stem. When it is desired to operate the ejector device, it is necessary to move the pivoted member into alignment with the ash ejector and then to push the ash ejector from the pipe. Such devices are rather cumbersome and detract from the general appearance of the pipe, particularly when the moveable arm member is moved to the open or operating position in line with the ash ejector.

It is therefore an object of the present invention to provide an ash ejector device in the bowl of the pipe which may be operated by an actuating means positioned on the lower part of the pipe stem but the actuating means does not move outside the confines or exterior surfaces of the pipe bowl and stem in order to operate or actuate the ash ejector.

Another object is to have an ash ejector device in the form of a grate upon which the tobacco charge is placed for smoking and which may be positioned by the smoker at any point in the pipe bowl. In this manner any amount of tobacco desired by the smoker may be charged into the pipe bowl and still obtain satisfactory and enjoyable smoking conditions. Through the employment of this feature in smoking, considerable tobacco may be saved if a short smoke is desired. In connection with the feature of being able to position the grate or ejector plate at any desired position while the pipe is being smoked, this feature also enables the smoker to loosen the charge and obtain freer draft in the bowl when the tobacco becomes packed by merely moving or actuating the ejector plate slightly.

Another object of my invention lies in the fact that through the use of the ejector plate which may be set in any desired position by means of the novel actuating means, the taste of the smoke may be controlled by the smoker. The smoker is able to adjust the position of the ejector plate with respect to the suction flue or bore in the stem and thereby may obtain a cool, warm, or hot smoke depending upon the smoker's desire. Furthermore, through the medium of a filter which may be placed on the upper surface of the ejector

plate, the smoke may be filtered or partially filtered, thereby controlling the taste of the smoke.

An additional object of my invention is to provide an actuating means to operate an ejector device in a pipe bowl by merely applying pressure on an operating knob, making it unnecessary to move a lever from the stem into alignment with the pipe bowl. The product of my invention does not have cumbersome elements which must be moved into awkward positions in order to operate ejector plates in smoking pipes.

A further object of my invention is to provide a slight bend or curvature in the flue or bore in the pipe stem at a point near the flue entrance into the pipe bowl. This feature enables the smoker to better control the taste of the smoke and also enables easier cleaning of the pipe by means of ordinary pipe cleaners. When a pipe cleaner is inserted into the stem the cleaner will be deflected upward into the pipe bowl and will thereby permit easy removal of the cleaner from the pipe.

Still further objects and advantages will present themselves and will be obvious as the nature of the invention is understood by those skilled in the art.

Broadly stated, my invention comprises an ejector plate positioned in the bowl of a pipe which is adapted to be operated up and down along the approximate vertical axis of the pipe bowl. A flexible spring element adapted to operate the ejector plate is positioned in a channel on the base portion of the pipe stem and has one end fastened to the lower side of the ejector plate. As the flexible spring element is moved back and forth in the channel of the pipe stem, the ejector plate will be moved up and down (raised and lowered) in the bowl of the pipe.

In the drawing

40 Figure 1 shows a side view of a conventional pipe with the ejector plate projecting above the upper edge of the pipe bowl.

45 Figure 2 shows a sectional view of a pipe disclosing the detail view of my invention with the ejector in the normal position.

Figure 3 is a plan view of an ejector plate which may be used in my invention.

Figure 4 is a plan view of a filter which may be used in conjunction with an ejector plate as illustrated in Figure 3.

Figure 5 is a sectional view along the lines 5—5 showing the groove along the base of the stem and the flexible spring means positioned in the groove.

Fig. 6 shows a sectional view of a portion of a pipe showing a modification of the invention.

In considering the drawing in more detail, Figure 1 shows a smoking pipe having a hollow bowl 1 and a stem 2. The pipe may be made of any suitable material ordinarily used in the manufacture of pipes such as briars, wood fibers molded with synthetic resinous binders, or the like. A longitudinally extending recess or groove-shaped portion extends from the base or bottom of the bowl forwardly along the lower exterior surface of the stem 2, and is so shaped as to form a guiding channel 3 having flanges or retaining edges 3a, for the spring element 4. The retaining edges of the guiding channel serve to retain within the boundaries of the channel that portion of the flexible spring which is in the channel. A flexible spring element 4 is inserted in slidable engagement in the guiding channel 3 and is adapted to be moved back and forth in the channel through the medium of the operating knob 5 which may be an integral part of or fastened to the flexible spring element by means of any conventional securing means 6 such as rivets or anchoring pins.

The guiding channel may be cut or molded directly into the material from which the pipe is manufactured or a guiding channel manufactured from metal, molded rubber, synthetic resins or the like may be fastened to the lower exterior portion of the pipe stem or may be inserted into a recess or groove formed in the lower portion of the stem. The pre-formed insert type of guiding channel is the preferable construction as contrasted to the type which is cut or molded into the body of the pipe stem because of less wearing action between the actuating spring 4 and the walls of the guiding channel 3. It is, however, understood that any type of guiding channel may be used in connection with my invention as long as it functions as a guiding means for the spring element 4 and when the term guiding channel or guiding means is used herein and in the claims, a broad interpretation shall be applied to the term consistent with the disclosure contained in the specification.

The guiding channel 3, as illustrated in Figure 2, is a preformed insert type placed in a groove formed in the lowest portion of the stem and has the forward edge 7 reversely bent. The reversely bent edge projects into a small slot cut in the stem 2. As the pipe mouthpiece 19 is pushed into the stem opening or flue, the guiding channel 3 is anchored securely into place. The other edge of the guiding channel is anchored by having the edge of the channel 3 projecting into a small slot as illustrated in Figure 2.

An ejector plate 8 is positioned in the pipe bowl and is fastened to the end of the flexible spring 4. The pipe bowl 1, has an opening 9 in the bottom thereof. A closure and deflecting means 10, which may be substantially L-shaped, having a slightly curved surface 11, adapted to properly guide the flexible spring 4, is fitted into the opening 9. The opening is substantially sealed excepting sufficient space is allowed between the substantially L-shaped closure and deflecting element and the pipe stem at point 12 to permit entrance of the flexible spring 4 into the pipe bowl 1. Free and easy sliding access of the flexible spring into the pipe bowl is essential for the proper operation of the ejector plate.

The ejector plate 8 may be a solid plate, preferably conforming to the shape of the bowl of the pipe and being substantially the same diameter

as the lower portion of the pipe bowl. It will be clear, however, that the diameter of the plate should be slightly less than the diameter of the approximate mid-portion of the pipe bowl since the ejector plate should be free for easy and free movements when actuated by the flexible spring 4. If desired, the ejector plate may be perforated with holes 13, as illustrated in Figure 3. The perforations enable the user of the pipe to develop better draft during smoking of the pipe. Also, if desired a filter 14, such as a paper filter or equivalent filters, may be used with the ejector plate and may be affixed to the plate by fastening to the pin 18. A filter paper 14, as shown in Figure 4, may have radially extending slits 15 cut into the paper for more efficient operation.

A bore or flue 16 extends through the stem 2 of the pipe and opens into the bowl 1. The bore or flue may continue in a straight line as illustrated at 16-b in Figure 2 or in a modified form, the flue may extend into the pipe bowl at an angle greater than a right angle, the angle as illustrated at 16-a in Figure 6 being measured at the approximate juncture point of the pipe bowl and the stem. If the stem flue continues as indicated at 16-b, the smoker may apply draft only from a point below the ejector plate; if, however, the pipe is constructed to include the curved or angular flue construction feature as 16-a, draft may be applied to the tobacco charge from above or below the ejector plate, depending upon the smoker's desire. As an illustration, if the flue construction 16-a is used and the ejector plate is in the lower portion of the pipe bowl, draft is applied to the charge from above the plate and the smoke will be relatively hot to the smoker. However, if the ejector plate is raised in the pipe bowl by means of the actuating spring 4 to a point above the flue opening, draft may be applied from below the plate and the smoke will be cooler as compared to the preceding example. In this manner the temperature and taste of the smoke which the smoker draws from the pipe can be controlled quite easily. Another desirable feature of the construction 16-a lies in the fact that the pipe may be easily cleaned since when a pipe cleaner is inserted into the bore or flue from the mouthpiece end of the pipe, the cleaner will curve upwardly into the pipe bowl as the cleaner reaches the curved or angular portion 16-a in the flue. This feature enables one to easily remove the pipe cleaner from the pipe bowl.

In using my pipe, the ejector plate is usually in the normal position as illustrated in Figure 2. When the ejector plate 8 is in the normal position, the operating knob 5 of the flexible spring 4 is moved or slid along the guiding channel 3 by applying pressure to the operating knob and moving it back towards the pipe bowl. As the knob is moved in the direction of the pipe bowl, the flexible spring will be guided through the opening 9 in the bottom of the bowl and upward through the approximate middle of the bowl. Due to the slight curvature of the flexible spring, the edge of the ejector plate 8 may tend to scrape on the wall 17 of the bowl, and, as the plate emerges from the top of the bowl as illustrated in Figure 1, the contents of the pipe will be emptied. Furthermore, through the scraping action of the plate on the side walls of the bowl, the pipe bowl will remain quite free and clean from excess charred residues or the like. Also, if a filter paper 14 is used on the ejector plate 8, the paper will be automatically loosened from the plate by the edge of the pipe bowl as the

ejector plate is returned to the normal position.

The ejector is returned to the normal position as shown in Figure 2 by merely applying pressure to the operating knob 5 and moving the knob forward toward the mouthpiece. In this action, the flexible spring will move downward through the pipe bowl and will then be deflected by the closure and deflecting means 10 into the guiding channel 3 in the lower portion of the pipe stem. As the knob 5 is returned to the approximate position in Figure 2, the ejector plate or grate will be in the lower portion of the bowl.

The spring 4 used in my invention may be made of flat, flexible spring steel, convex flexible spring steel, spring wire or any other flexible spring material which may be guided in channels and deflected around severe or sharp angles and still impart actuating force to the means to be actuated under the conditions enumerated. It is necessary that the spring has such properties which enable the direction of movement to be changed by deflecting means or guiding means without losing its ability to move the ejector plate as described above.

The construction of my pipe is simple and does not involve any change in standard pipe design. In fact, my invention may be applied and embodied in any standard forms of tobacco pipes now in general use, such as straight stem pipes as illustrated in the attached drawing and also pipes having curved stems.

While I have described my invention in considerable detail comprising the preferred construction, it will be understood, however, that variations may be made herein without necessarily departing from the scope and spirit of the invention as defined in the following claims.

I claim:

1. A smoke pipe comprising a bowl and an angularly disposed stem having a guiding channel extending from the bottom of the bowl forwardly along the outside surface of the lower portion of said stem, an ejector plate positioned in the bowl and flexible means fastened to the plate and extending into the guiding channel of the stem, said flexible means being free to slide back and forth in the channel of the stem and serving to simultaneously actuate the ejector plate in the bowl of the pipe.

2. A smoke pipe comprising a bowl and an angularly disposed stem having a guiding channel extending from the bottom of the bowl forwardly along the outside surface of the lower portion of said stem, an ejector plate positioned in the bowl, flexible means fastened to the plate and extending into the channel portion of the stem, and means to retain a portion of the flexible means within the boundaries of the channel, said flexible means being free to slide back and forth in the channel of the stem and serving to simultaneously actuate the ejector plate in the bowl of the pipe.

3. A smoke pipe comprising a bowl and an angularly disposed stem having a guiding channel extending from the bottom of the bowl forwardly along the outside surface of the lower portion of said stem, an ejector plate positioned in the bowl, flexible means fastened to the plate and extending into the channel portion of the stem, and means to retain a portion of the flexible means within the boundaries of the channel, said flexible means being free to slide back and forth in the channel of the stem and serving to simultaneously actuate the ejector plate up and down in the bowl of the pipe.

4. A smoke pipe comprising a bowl having an opening in the bottom portion, a stem formed with a guiding channel extending from the bottom of the bowl forwardly along the outside surface of the lower portion of said stem, an ejector plate positioned in the bowl, flexible means slidably mounted in the guiding channel of the stem, and means to retain a portion of the flexible means within the boundaries of the channel, said flexible means being fastened to the ejector plate thence passing through the opening in the lower portion of the bowl and extending into the guiding channel of the stem, whereby as the flexible means is slid back and forth in the guiding channel said plate is actuated in the bowl of the pipe.

5. A smoke pipe comprising a bowl having an opening in the bottom portion, a stem formed with a guiding channel extending from the bottom of the bowl forwardly along the outside surface of the lower portion of said stem, an ejector plate positioned in the bowl, flexible means slidably mounted in the guiding channel of the stem, and means to retain a portion of the flexible means within the boundaries of the channel, said flexible means being fastened to the ejector plate thence passing through the opening in the lower portion of the bowl and extending into the guiding channel of the stem, whereby as the flexible means is slid back and forth in the guiding channel said plate is actuated in the bowl of the pipe.

6. A smoke pipe comprising a bowl having an opening in the bottom portion, a stem having a guiding channel extending from the bottom of the bowl forwardly along the outside surface of the lower portion of said stem, a deflecting means fitted in the opening in the bottom portion of the bowl, an ejector plate positioned in the bowl of the pipe, flexible means fastened to the ejector plate and slidably extending in contact with the deflecting means into the guiding channel of the stem, and means to retain a portion of the flexible means within the boundaries of the channel, whereby as the flexible means is moved back and forth in the guiding channel of the stem said ejector plate is actuated in the bowl of the pipe.

7. A smoke pipe comprising a bowl having an opening in the bottom portion, a stem having a guiding channel extending from the bottom of the bowl forwardly along the outside surface of the lower portion of said stem, a deflecting means fitted in the opening in the bottom portion of the bowl, an ejector plate positioned in the bowl of the pipe, flexible means fastened to the ejector plate and slidably extending in contact with the deflecting means into the guiding channel of the stem, and means to retain a portion of the flexible means within the boundaries of the channel, whereby as the flexible means is moved back and forth in the guiding channel said ejector plate is raised or lowered in the bowl of the pipe.

8. A smoke pipe comprising a bowl having an opening in the bottom portion, a stem having a flue extending substantially through the longitudinal center opening into the bowl and having a guiding channel extending from the bottom of the bowl forwardly along the outside surface of the lower portion of said stem, an ejector plate positioned in the bowl, a deflecting means fitted in the opening in the bottom of the bowl, flexible means fastened to the ejector plate extending in slidable contact with the deflecting means

into the guiding channel of the stem, and means to retain a portion of the flexible means within the boundaries of the channel, whereby as the flexible means is moved back and forth in the guiding channel said ejector plate is raised and lowered with relation to the flue opening in the bowl of the pipe.

9. A smoke pipe comprising a bowl with an ejector plate positioned in the bowl, a flexible means and a stem having a guiding channel extending from the bottom of the bowl forwardly along the outside surface of the lower portion of said stem and having a flue extending through the body thereof to a point of the approximate juncture line of the stem and bowl thence being extended upwardly at an angle with respect to the pipe stem and opening into the lower half of the pipe bowl, said flexible means being fastened to the ejector plate thence slidably extending into the guiding channel of the stem, and means to retain a portion of the flexible means within the boundaries of the channel, whereby as the flexible means is slid back and forth in the guiding channel said ejector plate is raised and lowered in the bowl with relation to the flue opening in the bowl of the pipe.

10. A smoke pipe comprising a bowl and an angularly disposed stem having a guiding channel

extending from the bottom of the bowl forwardly along the outside surface of the lower portion of said stem, an ejector plate positioned in the bowl, flexible means fastened to the plate and 5 extending into the channel portion of the stem, and means comprising flanges to retain a portion of the flexible means within the boundaries of the channel, said flexible means being free to slide back and forth in the channel of the stem and serving to simultaneously actuate the ejector plate in the bowl of the pipe.

11. A smoke pipe comprising a bowl having an opening in the bottom portion, a stem having a guiding channel extending from the bottom of the bowl forwardly along the outside surface of the lower portion of said stem, a deflecting means fitted in the opening in the bottom portion of the bowl, an ejector plate positioned in the bowl of the pipe, flexible means fastened to the ejector plate and slidably extending in contact with the deflecting means into the guiding channel of the stem, and means comprising flanges to retain a portion of the flexible means within the boundaries of the channel, whereby as the flexible means is moved back and forth in the guiding channel of the stem said ejector plate is actuated in the bowl of the pipe.

FRED W. GANS.
